UNITED STATES PATENT OFFICE

152,194

DESIGN FOR AN ASH TRAY

William Forthman, Buchanan, Mich.

Application February 21, 1948, Serial No. 144,659

Term of patent 7 years

(Cl. D85—2)

To all whom it may concern:

Be it known that I, William Forthman, a citizen of the United States, residing at Buchanan, in the county of Berrien and State of Michigan, have invented a new, original, and ornamental Design for an Ash Tray, of which the following is a specification, reference being had to the accompanying drawings, forming a part thereof.

In the drawings:

Fig. 1 is a top plan view of an ash tray, showing my new design;

Fig. 2 is a right hand side perspective view thereof; and

Fig. 3 is a left hand side perspective view thereof.

I claim:

The ornamental design for an ash tray, as shown.

WILLIAM FORTHMAN.
